United States Patent Office

Des. 204,725
Patented May 10, 1966

204,725

SKI PACK

Norman W. Selnes, 3725 W. Outer Drive,
Detroit, Mich. 48221

Filed Apr. 13, 1965, Ser. No. 84,766

Term of patent 14 years

(Cl. D87—5)

FIG. 3

FIG. 4

FIG. 5

FIG. 1 is a front view in perspective of a ski pack embodying my new design;

FIG. 2 is a side elevational view of the left side of the ski pack as viewed in FIG. 1;

FIG. 3 is a top plan view;

FIG. 4 is a bottom view; and

FIG. 5 is a rear elevational view.

I claim:

The ornamental design of a ski pack, substantially, as shown.
